JOHN B. DAVIS, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

MEASURING-PUMP FOR OIL AND THE LIKE.

1,275,866.

Specification of Letters Patent. Patented Aug. 13, 1918.

Application filed July 17, 1916. Serial No. 109,834.

To all whom it may concern:

Be it known that I, JOHN B. DAVIS, a citizen of the United States of America, residing in Springfield, in the county of 5 Hampden and State of Massachusetts, have invented certain new and useful Improvements in Measuring-Pumps for Oil and the like, of which the following is a specification.

10 This invention relates to improvements in dispensing or measuring pumps, such as are commonly used in the dispensation of gasoline and like oils.

Such pumps are generally of the piston 15 type, which has been found to be most satisfactory on account of its accurate measuring qualities. Moreover, these pumps are commonly single acting pumps, and the pistons thereof are arranged for reciprocation by a 20 rack and pinion device. The principal disadvantages incident to such construction are twofold, namely, intermittent flow, since the pump delivers on one stroke only, and inconvenient operation, since the pinion is 25 usually actuated by a crank which must be turned first in one and then in the opposite direction. This invention is concerned with the elimination of these disadvantages in an improved manner and more particularly 30 with a simple structural addition to single acting piston pumps whereby the flow therefrom may be rendered continuous.

This structural addition takes the form of a small cylinder and a piston secured to the 35 piston rod of the main piston and slidable within the small cylinder. Such additional cylinders have been used before, as I am aware, but the structure hereinafter disclosed has certain novel and advantageous 40 features over the prior art. For example, heretofore the additional cylinder has been either entirely closed in or left entirely open to the air with the disadvantage in one case of a back pressure on the small piston or 45 in the other case of a possibility of injury to the walls of the small cylinder and piston through dirt, grit, and other foreign substances lodging in the cylinder through its open upper end. This invention seeks to 50 eliminate both the disadvantages mentioned.

An object of this invention is to provide in a single acting piston pump, a primary cylinder adapted to receive liquid from a

suitable supply tank, a secondary cylinder 55 within the primary cylinder and primary and secondary pistons slideable respectively within the primary and secondary cylinders, together with a connection between the upper portion of the secondary cylinder and the air space of the supply tank, the secondary cylinder being closed at its upper 60 end, whereby foreign substances are prevented from lodging therein, the construction being characterized by a surging of fluid, preferably air, to and from the upper 65 portion of the secondary cylinder whereby back pressure on the secondary piston is eliminated.

Another object of the invention is to provide in a pump of the class described improved means to reciprocate the pistons, said means arranged for operation by continuous rotation in one direction and characterized by an improved arrangement for varying 75 the stroke of the pistons.

Another object of the invention is to provide an improved measuring pump, adapted to deliver a definite measured quantity for each revolution of the operating means, together with apparatus to count and register 80 said revolutions and thus indicate the measured quantities dispensed.

Other objects and advantages will appear in the detailed description to follow and in the appended claims.

For the purpose of illustrating one way in which the invention may be practised, a single preferred embodiment thereof is shown in the accompanying drawings, in which—

Fig. 1 is an elevational view, with parts 90 in section, of the dispensing and measuring pump;

Fig. 2 is a sectional elevation drawn to an enlarged scale and taken on the line 2—2 of Fig. 1 and looking in the direction of the 95 arrows;

Fig. 3 is an enlarged sectional elevation taken on the line 3—3 of Fig. 1 and looking in the direction of the arrows;

Fig. 4 is an enlarged sectional view taken 100 on the line 4—4 of Fig. 3 and looking in the direction of the arrows;

Fig. 5 is an enlarged sectional view taken 105 on the line 5—5 of Fig. 3 and looking in the direction of the arrows;

Fig. 6 is a sectional view taken on the

line 6—6 of Fig. 3 and looking in the direction of the arrows;

Fig. 7 is a sectional plan view taken on the line 7—7 of Fig. 3 and looking in the direction of the arrows; and

Fig. 8 is a diagrammatical view of the operating mechanism for the piston rod.

Referring to these drawings in detail, the frame of the pump comprises a pedestal A which forms a housing for the pump cylinders, a casting B which closes the top of pedestal A and forms a support for the pump cylinders, and a substantially U-shaped yoke C mounted upon plate B with the cross bar of the U in spaced relation above the latter. Within yoke C and above plate B is located the pump operating mechanism and the counting and registering apparatus to be described. If desirable, doors D may be mounted on yoke C to inclose the apparatus housed therein, as clearly shown in Figs. 3 and 7.

The pump cylinders and associated devices will first be described. The casting B is formed with axially aligned sockets 1 and 2 to receive sleeves 3 and 4, which constitute secondary and primary cylinders respectively, and the sockets, as shown in Figs. 1 and 2, extend above and below plate B, respectively. Sleeve 3 has a relatively large bearing in socket 1 and is held therein by a driving fit so that it depends into the lower socket 2 spaced therefrom and in concentric relation. The lower end of sleeve 4 is closed by a cap 5, and the latter is held to plate B by suitable tie rods 10, portions of the latter being indicated in Fig. 3. Cap 5 has a central chamber 6 which is in communication with a supply pipe 7, and the outlet of chamber 6 is normally closed by a suction operated valve 8. Above the latter is a suitable filter 9 which is supported upon the upper face of cap 5, as shown in Figs. 1 and 2.

Slidably mounted in sleeves 3 and 4 are pistons 11 and 12, respectively, which are fixed as shown to a common piston rod 13. The latter extends upwardly through a suitable stuffing box, as shown in Fig. 2, and is adapted to be reciprocated by means to be described. The lower piston 12 only has valves and is of the type more fully disclosed in my copending application Serial No. 61397, filed November 13, 1915. For the present purposes, it will suffice to say that piston 12 has a plurality of apertures 14 therein which are normally closed by a spring pressed strip 15 of leather or the like, which strip also forms the packing for the piston. The upper piston 11 is similar, but the apertures are omitted, and it simply has the spring pressed strip to prevent leakage past the piston. The socket 1 is closed at the top, as shown in Figs. 1 and 2, and the space above piston 11 is adapted to be con-

nected to the air space of the tank which supplies pipe 7 by a pipe 16, a cored passage in member B (Fig. 2) and a small orifice 16' in sleeve 3. Thus, the space above piston 11 is adapted to be filled at all times with air which surges back and forth between the space in sleeve 3 and the supply tank by pipe 16. It has been found that, in practice, a slight leakage occurs which is caused by slow seepage of the fluid through the packing strip 15. It is also to be noted that the cored passage in member B is connected to the interior of the sleeve by a small orifice, which is adapted to be closed by piston 11 when at the upper end of its stroke. It is proposed to leave the piston 11 at the upper end of its stroke when the pump is idle to prevent loss of the charge in the lower part of the sleeve 3, so that the accuracy of a subsequent delivery from the pump will be unaffected. Socket 2 has a delivery chamber 17 therein which extends around the exterior of sleeve 3, and leading vertically upward from chamber 17 on opposite sides of sleeve 3 are pipes 18 and 19 which are delivery and expansion pipes, respectively. Preferably, a suitable nonreturn valve 18' is interposed in the delivery pipe which is arranged to prevent the entrance of air to the cylinders. The lower cap 5 has an annular cored chamber 20 into which all sediment and water, held from passing into the pump by filter 9, is adapted to pass, and a small pipe 21, in communication with this chamber, extends vertically upward through plate B and is provided at its upper end with a valve 22. The latter is provided for the purpose of "blowing off" the filter, when desired. This is accomplished by closing off delivery pipe 18, opening valve 22, and thereafter operating the pump, whereby the water and sediment in chamber 20 will be forced through pipe 21.

The operating mechanism for the pump will next be described with particular reference to Figs. 3 to 8, inclusive. Piston rod 13 extends entirely through yoke C and is concealed by an ornamental cap 24 which permits the requisite travel of rod 13 therein. Coiled around rod 13 and held between a collar on the latter and the upper face of yoke C is a spring 25. A similar spring 26 is supported below yoke C on a collar pinned to rod C, as best shown in Fig. 3. These springs are arranged to be alternately compressed against yoke C as rod 13 nears its dead center positions with the idea of preventing the "jump" experienced when, as here, the rod is reciprocated by a crank handle, continuously rotatable in one direction. By thus providing some resistance, where otherwise little exists, the resistance

to turning of the operating handle is made substantially uniform.

Fixed to yoke C, as shown in Fig. 7, is a cross bar F. Referring to Fig. 3, rotatable in the cross bar F is a shaft 27, and pinned to the latter is a crank 28 which is connected by a link 29 to rod 13 by a suitable clamp, as shown in Figs. 3 and 8. Loosely mounted on shaft 27 and held from axial movement by the collar shown is a crank handle 30, the interior construction of which is illustrated in Fig. 5. Pivoted in handle 30 is a pawl 31 normally held in engagement with the shaft 27 by the spring shown. A pin 32 is driven diametrically through shaft 27 and its protruding ends are filed off to form ratchet teeth. When handle 30 is rotated in the direction of the arrow, shown in Fig. 5, shaft 27 is rotated, and the pawl and ratchet construction permits the handle to be turned in an opposite direction without rotating the shaft.

The crank 28 is best shown in Fig. 4 and is arranged for adjustment to obtain a variable throw. A slot 33 therein receives the crank pin 34 which may be clamped to the crank by nut 36 and a flange 37 on pin 34 (Fig. 3). A screw 35, threaded through pin 34, is coextensive in length with the slot 33 and has rounded ends to engage the extremities of the latter, as shown in Fig. 4. The outer end of screw 35 has a square hole 38, therein adapted to receive a socket wrench which may be inserted in the opening 39 in the end of crank 28. A small hole 40 permits a wire to be passed therethrough and diametrically across opening 39 and, if desired, the ends of this wire may be brought together and sealed, to prevent its removal whereby fraudulent change of adjustment and the subsequent deliveries of inaccurately measured quantities may be prevented.

The counting and registering apparatus will now be described with particular reference to Figs. 3, 6, and 7. Rotatably mounted in a cross bar E fixed to yoke C is a shaft 42 and pinned thereon is a cam 43 and a slotted operating crank 44. A rod 45 fixed in link 29 is suitably bent so that its extremity lies exactly opposite crank pin 34 and so that it clears piston rod 13 at all points in its rotation. The extremity of rod 45 lies in the slot in crank 44, as shown in Fig. 6, so that bar E and the mechanism thereon may be quickly and conveniently connected or detached without disturbing the operating mechanism. Fixed to plate E by screws 46 (Fig. 6) is a ring casting 47 (Fig. 3) having an outer flange spaced from the plate. A dial ring 48 and a ratchet 49 held together by screws 50 (Fig. 3) are rotatable upon the periphery of ring 47 and are held axially between the flange on the latter and plate E. Pivoted intermediate

its ends at 51 to plate E (Fig. 6) is a lever 52, the lower end of which is held against cam 43 by a spring 53. Extending through the upper end of lever 52 is a pin 54 having a head thereon at one end to rest against the lever, as shown in Fig. 3, and a pawl 55 pinned thereto at the other end. Passing loosely through the head of pin 54 (Figs. 3 and 6) is a spring 56 which is secured to lever 52, as shown in Fig. 6. This spring is arranged to hold pawl 55 in engagement with ratchet 49 and, when the pawl is moved, pin 54 moves therewith and bends spring 56. A holding pawl 57 is similarly mounted in plate E, as shown in Fig. 6.

It will be obvious from the foregoing description that one complete revolution of handle 30 will move ratchet 49 the distance of one tooth and the rim 48 as well. The latter has fixed thereon a face dial 60 (Fig. 1) and a peripheral dial 61 (Fig. 7). Both dials are graduated in suitable units, such as gallons, for example, and the indications of these dials may be read by reference to pointers 62 and 63, respectively, which are fixed to plate E, as shown in Figs. 1, 3, and 7. Fixed to plate E and arranged centrally within the opening in ring 47 is a total register 64 which is of the usual construction and well known by those skilled in the art. This register is adapted to be actuated from a small crank 65 fixed to the end of shaft 42, as shown in Fig. 3. The readings of register 64 are cumulative and indicate the total quantity delivered from the pump for any period. Dials 60 and 61, however, are adapted to indicate merely the quantity dispensed to one customer and are arranged to be reset by turning the rim 48 in a counterclockwise direction until the zero marks lie in under the pointers. A pin 66 (Figs. 1, 3, and 7) is fixed to rim 48 to permit convenient turning thereof for resetting purposes. It is to be noted that dial 60 is so arranged as to be conveniently visible to the customer while dial 61 and register 64 are arranged for convenient reading by the pump operator.

The dials just described are arranged to count the revolutions of handle 30, each of the smallest scale divisions representing one revolution. The pump itself is first adjusted by screw 35 to deliver the desired quantity per revolution, say, for example, one quarter of a gallon. Having made this preliminary adjustment, the readings of dials 60 and 61 will indicate gallons and fractions thereof as four revolutions of ratchet 49 will bring the numerals 1 on dials 60 and 61 in under their respective pointers 62 and 63. The variable throw crank 28 may be, if desired, moved so that one revolution of crank 30 effects the delivery of one quarter of a Canadian gallon, or, if desired, a liter. In the latter instance, new dials would, how-

ever, be provided which are similarly graduated but have different designations for more convenient reading.

The operation of the pump will now be described with reference to Figs. 1 and 2. With the parts positioned as in Fig. 2 an upward stroke of piston 12 will create a partial vacuum, lift valve 8 from its seat, and draw in a charge of liquid from pipe 7. Upon a succeeding down stroke, valve 8 is forced to its seat, and the liquid is forced through openings 14 and past strip 15 into the upper portion of sleeve 4. The next up stroke of piston 12 will force liquid through delivery pipe 18 but not, however, all the charge drawn in for pistons 11 and 12 move together and part, approximately half, of the charge, passes into sleeve 3, as piston 11 recedes, to be delivered through pipe 18 on the down stroke of piston 11. The expansion pipe 19 is arranged to act in the well known manner as an air dome and assists with the piston 11 and sleeve 3 in making the flow through pipe 18 substantially uniform and continuous. Thus, by the addition of piston 11 and sleeve 3 to a single acting pump, the flow therefrom is made continuous as the operating handle is continuously turned in one direction.

It is not desirable to have cylinder 3 open to the air as has been done heretofore for such construction permits dust, dirt, and foreign substances to collect therein, which substances are in time ground between the piston 11 and its cylinder to the detriment of both. Neither is it desirable to have the cylinder 3 closed in the ordinary manner for the reason that an undesirable back pressure is then encountered by piston 11. The important feature of the construction working as described is that the cylinder 3 is closed at the top without having the usual undesirable back pressure, for the space above piston 11 is filled with fluid which surges back and forth in pipe 16. Thus on the down stroke of rod 13 piston 12 is forcing its way through the liquid drawn into sleeve 4 on the preceding stroke and piston 11 is drawing in a charge of air from the supply tank which charge is redelivered to the tank on the succeeding stroke.

Thus, by the simple addition of cylinder 3 to a single acting pump in the manner disclosed, a continuous delivery may be secured therefrom and the particular arrangement is characterized by its reduction of back pressure on, and by its prevention of damage by foreign substances to, the additional cylinder. It is recognized that modifications may be made in the specific structure herein described for illustrative purposes without departing from the scope of the invention which is defined by the appended claims rather than by the foregoing description of one preferred form.

What I claim is—

1. The combination with a main piston pump of a secondary cylinder communicating at one end with the pump cylinder and arranged to receive part of the lifted charge for delivery on the return stroke of the pump, a secondary piston slideable in the secondary cylinder and movable with the pump piston, the other end of the secondary cylinder being entirely closed to the atmosphere, and means for connecting the upper portion of the secondary cylinder to a fluid supply chamber, all constructed and arranged so that fluid may surge back and forth from the upper portion of the secondary cylinder through said connecting means.

2. The combination with a main piston pump operable to deliver liquid from a supply tank, of a secondary cylinder communicating at one end with the pump cylinder and arranged to receive part of the lifted charge for delivery on the return stroke of the pump, a secondary piston slideable in the secondary cylinder and movable with the pump piston, the secondary cylinder having its other end entirely closed to the atmosphere, and means adapted to connect the upper portion of the secondary cylinder to the air space of the supply tank, all constructed and arranged so that air may surge back and forth from the upper portion of the secondary cylinder through said connecting means.

3. The combination in a measuring pump with a piston rod thereof, spaced supports between which said rod is arranged to travel, a crank-shaft rotatable in one of said supports, a link connecting the crank-shaft and rod to reciprocate the latter on rotation of the crank-shaft, a counting apparatus mounted on the other support, and an actuating member for the apparatus, said member connected to said link and bent in U-form to clear said rod.

4. The combination in a measuring pump with the piston rod thereof, spaced supports between which said rod is arranged to travel, a pump-actuating shaft rotatable in one of the supports, a register-operating shaft aligned with the actuating shaft and rotatable in the other support, cranks on each shaft, means to connect said cranks one to the other and to said rod so that a rotation of one will reciprocate said rod and will rotate the other shaft without interfering with the reciprocatory movement of said rod.

5. The combination in a double-acting measuring pump with the pistons and a common piston rod therefor, of a crank-shaft operatively connected to the rod to reciprocate the latter on continuous rotation of said shaft in one direction, a frame supporting said shaft and having a part through which said rod is arranged to pass, a crank handle to turn said shaft, abutments on said

rod one on each side of said part, and a spring between each abutment and said part, each spring arranged to be compressed between its abutment and said part only as the 5 piston approaches a dead center position and to exert a gradually increasing and then a gradually decreasing resistance as the piston moves toward and away from a dead center position, whereby said handle may turn 10 smoothly under a substantially constant effort throughout a cycle of operation of the piston.

6. A measuring pump, comprising, a hollow pedestal, a cover plate therefor, pump 15 cylinders supported by and depending from the latter, a common piston rod for the cylinders extending above said plate, a U-shaped yoke supported from the latter having a central bearing for said rod, a crank 20 shaft supported from the yoke on one side of said rod, and a link connecting the latter to the crank shaft, whereby the rod may be reciprocated on a rotation of said shaft, a counting apparatus supported from the yoke

on the other side of said rod, and an actuating member therefor connected to the link and bent in U-form to clear said rod. 25

7. A pump, comprising, axially aligned cylinders of different diameters, one thereof having an upper end closed to the atmosphere and arranged within the other cylinder at the outlet end thereof, a cap at the base of the larger cylinder having a valve controlled inlet therein adapted to be connected to a liquid supply tank, valved and 30 valveless pistons slidable respectively in the large and small cylinders, a common piston rod connecting said pistons and extending through the top of the smaller cylinder, means to reciprocate said rod, and means 35 adapted to connect the upper portion of the smaller cylinder to the air space of said tank, all constructed and arranged so that a continuous flow is obtained from the pump and so that air may surge back and forth 40 from the upper portion of the secondary cylinder through said connecting means. 45

JOHN B. DAVIS.
